TELEVISION CABINET

William Joseph Genter, Van Nuys, Calif.

Application September 5, 1952, Serial No. 21,337

Term of patent 14 years

(Cl. D56—4)

Fig. 2.

Fig. 1.

To all whom it may concern:

Be it known that I, William Joseph Genter, a citizen of the United States, residing in the city of Van Nuys, in the county of Los Angeles, State of California, have invented a new, original, and ornamental Design for a Television Cabinet of which the following is a specification.

I claim:

The ornamental design for a television cabinet, as shown.
